E. F. O'HAVER.

ROTARY ENGINE.

APPLICATION FILED MAR. 15, 1916.

1,223,100.

Patented Apr. 17, 1917.

UNITED STATES PATENT OFFICE.

EDWARD FRANCIS O'HAVER, OF CARLISLE, INDIANA.

ROTARY ENGINE.

1,223,100.

Specification of Letters Patent. Patented Apr. 17, 1917.

Application filed March 15, 1916. Serial No. 84,310

To all whom it may concern:

Be it known that I, EDWARD F. O'HAVER, a citizen of the United States, and a resident of Carlisle, in the county of Sullivan and State of Indiana, have invented a new and Improved Rotary Engine, of which the following is a full, clear, and exact description.

The invention relates to rotary engines, such as shown and described in the Letters Patent of the United States No. 1,176,481, granted to me on March 21, 1916.

The object of the present invention is to provide a new and improved rotary engine which is simple and durable in construction and arranged to permit of regulating the gas and air for the explosive mixture to a nicety and to insure the admission of the explosive mixture into the working chamber of the engine at the proper time.

The invention is hereinafter described and represented in the accompanying drawings forming a part of this specification, in which similar characters of reference indicate corresponding parts in all the views.

Figure 1 is a side elevation of the rotary engine;

Fig. 2 is a similar view of the same with parts shown in section;

Fig. 3 is a sectional plan view of the same on the line 3-3 of Fig. 2;

Fig. 4 is a plan view of the regulating device for regulating the amount of gas and air passing into the pressure supply and ignition chamber; and

Fig. 5 is a cross section of the cylinder and rotor.

The cylinder 10 of the engine is provided with a suitable base 11 for supporting the engine on a suitable foundation. In the cylinder 10 rotates a rotor 12 having its shaft 13 journaled in suitable bearings 14, and the rotor 12 has its rim made in U shape or recessed in its peripheral face to provide an annular working chamber 15 in which extends a piston 16 integral with the bottom and sides of the rim and in contact at its outer end with the inner surface of the cylinder 10. Into this channel or working chamber 15 are adapted to pass abutment

arms 17 of an abutment wheel 18 having a shaft 19 journaled in suitable bearings arranged on a casting 20 attached to or forming part of the cylinder 10. The piston head 16 is adapted to engage the arm 17 in 55 position at the time in the working chamber 15 to impart an intermittent rotary motion to the wheel 18 to allow the piston head to pass the said arm.

A pressure supply and ignition chamber 25 opens into the working chamber 15 adjacent one side of the casting 20, and this chamber 25 is provided with an ignition device 26 of the usual construction. The pressure supply and ignition chamber 25 is 60 connected by ports 27, 28 with an air supply chamber 29 and a fuel supply chamber 30. The air chamber 29 is provided with an air inlet pipe 31 and the fuel chamber 30 is provided with a suitable supply pipe 32 connected with a suitable source of gas supply. Within the chambers 29 and 30 are mounted to turn cylindrical valves 33, 34, of which the valve 33 is provided at opposite sides with ports 35, 36 adapted to register with 65 the pipe 31 and the port 27, respectively. Similar ports 37, 38 are arranged in the valve 34 and register with the port 28 and the supply pipe 32 respectively. The stems 39, 40 of the valves 33 and 34 extend to 70 the outside of the chambers 29 and 30, and on the outer end of the stem 39 is secured a segmental gear wheel 41 in mesh with a segmental gear wheel 42 secured on the stem 40. The segmental gear wheel 42 is provided with a handle 43 under the control of the operator for turning the stem 40 and with it the valve 34 and at the same time turning the gear wheel 42 in mesh 75 with the gear wheel 41 to turn the stem 39 and consequently the valve 33. By this arrangement the ports 35, 36 and 37, 38 can be opened more or less relatively to the pipe 31, port 27 and port 28 and pipe 32. The segmental gear wheel 42 is provided with 80 a pointer 44 indicating on a scale 45 the relative positions of the valves 33 and 34 in the chambers 29 and 30.

The ports 27 and 28 are opened and closed by valves 50 and 51 provided with valve 85

stems 52, 53 slideable in bearings 54, attached to the cylinder 10. The outer ends of the valve stems 52, 53 are provided with friction rollers 55, 56 in engagement with the peripheral faces of cams 57 and 58 secured on a shaft 59 journaled in suitable bearings 60 attached to the cylinder 10. The springs 61 press the stems 52 and 53 in an outward direction to hold the friction rollers 55, 56 in peripheral engagement with the cams 57 and 58.

The abutment wheel 18 is locked against rotation until the piston head 16 nears the arm 17 in position at the time in the working chamber 15, and then the abutment wheel 18 is automatically unlocked to allow the piston head 16 to turn the abutment wheel 18. This locking device for the abutment wheel 18 consists of a wheel 62 secured on the shaft 19 outside of the casing 20, and this wheel 62 is provided with notches 63 adapted to be engaged by a spring-pressed bolt 64 mounted to slide in bearings arranged on a bracket 65 attached to or forming part of the cylinder 10. The spring-pressed bolt 64 is provided with a pin 66 slidably engaging a slot 67 formed in the bracket 65 to hold the bolt 64 against turning. The pin 66 is adapted to be engaged by a cam lug 70 secured on a sprocket wheel 71 mounted to rotate loosely on the shaft 19. Around the sprocket wheel 71 passes a sprocket chain 72 which also passes around a sprocket wheel 73 secured on the rotor shaft 13 and the sprocket chain 72 also passes around a sprocket wheel 74 secured on the cam shaft 59, previously mentioned.

When the motor is running and the rotor 12 rotates in the direction of the arrow α then a traveling motion is given to the sprocket chain 72 in the direction of the arrow b whereby the sprocket wheel 71 is turned in the direction of the arrow c and its cam lug 70 periodically strikes the pin 66 and thereby moves the bolt 64 out of engagement with the corresponding notch 63 at the time the piston head 16 nears the arm 17 in position at the time in the working chamber 15. Thus the abutment wheel 18 is unlocked to allow the piston head 16 to turn the abutment wheel 18 and thus bring the next following arm 17 in position in the working chamber 15. The piston head 16 after passing the arms 17 also passes the inlet end of the pressure supply and ignition chamber 25 so that the explosive mixture passes from this chamber 25 into the working chamber and is at the same time ignited by the ignition device 26 to cause the rotor 12 to receive an impulse and thus be driven in the direction of the arrow α . An exhaust pipe 80 leads from the cylinder 10 adjacent the side of the casing 20 opposite the one at which the chamber 25 is locked so that the

products of combustion in front of the piston head 16 can escape to a suitable place of discharge.

The abutment wheel 18 is preferably provided with four arms spaced equidistantly apart and of which one extends radially into the working chamber 15 while the others are within the casing, as plainly shown in Fig. 2.

Having thus described my invention, I claim as new and desire to secure by Letters Patent:

1. A rotary engine, comprising a cylinder, a rotor mounted to turn therein and forming with the cylinder an annular working chamber, the rotor having a piston head, an abutment wheel having arms adapted to move successively into the said working chamber and adapted to be engaged by the said piston head, locking means for locking the said abutment wheel against turning, driving means driven from the said rotor controlling the said locking means to unlock the said abutment wheel prior to the piston head reaching the abutment arm in position in the working chamber at the time, a pressure supply and ignition chamber opening into the said working chamber adjacent the abutment wheel, a gas chamber connected with a gas supply and having a port leading into the said pressure supply and ignition chamber, an air chamber having a port opening into the said pressure supply and ignition chamber, valves controlling the said ports and provided with spring-pressed stems, a cam shaft having arms controlling the said valve stems and valves, and driving means for driving the said cam shaft and controlled from the said rotor, the said driving means for the abutment wheel and the said driving means for the said cam shaft having a driving member common to both.

2. A rotary engine, comprising a cylinder, a rotor mounted to turn therein and forming with the cylinder an annular working chamber, the rotor having a piston head, an abutment wheel having arms adapted to move successively into the said working chamber and adapted to be engaged by the said piston head, locking means for locking the said abutment wheel against turning, driving means driven from the said rotor controlling the said locking means to unlock the said abutment wheel prior to the piston head reaching the abutment arm in position in the working chamber at the time, a pressure supply and ignition chamber opening into the said working chamber adjacent the abutment wheel, a gas chamber connected with a gas supply and having a port leading into the said pressure supply and ignition chamber, an air chamber having a port opening into the said pressure supply and ignition chamber, valves controlled from the rotor

and controlling the said ports, and manually controlled setting means in the said gas chamber and the said air chamber for regulating the gas and air passing into the said gas and air chambers and into the said supply and ignition chamber:

In testimony whereof I have signed my

name to this specification in the presence of two subscribing witnesses.

EDWARD FRANCIS O'HAVER.
